UNITED STATES PATENT OFFICE

OLIVER B. PARKER, OF BROOKLYN, NEW YORK, ASSIGNOR TO PACENT ELECTRIC COMPANY, INC., OF NEW YORK, N. Y., A CORPORATION OF NEW YORK

ELECTROMAGNETIC REPRODUCER

Application filed July 19, 1930. Serial No. 469,069.

Special objects of the present invention are to provide a reproducer for electric phonographs and the like, which will be of simple, practical construction, small compact design, and which will have inherent self-damping characteristics.

The novel features of the invention by which the foregoing and other desirable objects are attained will appear from the following specification.

The drawing which forms part of the specification is illustrative of a simple commercial embodiment of the invention, it being appreciated that the structure may be modified and changed in various ways without departure from the true spirit and broad scope of the invention.

Fig. 1 is a top plan view of the device; Fig. 2 is a front view of the same; Fig. 3 is a bottom plan view.

A strong magnetic field is provided in the form of the invention shown, by a permanent U-magnet 5 of general horseshoe shape. Pole pieces 6, 7, are suitably connected to the arms of this U-magnet and a coil 8a is supported within the hollows of these pole pieces, which latter, as particularly shown in Fig. 2 are of general C-form and placed in opposing relation, so as to provide pole tips 6a, 7a, 3b, 7b, forming the two magnetic gaps at 8 and 9.

Mounted for operation between the pole pieces is an armature or reed 10 extending freely through the open center of the coil and terminating in a blade portion 11, bridging the upper magnetic gap 8. A special feature of this armature blade is that it extends substantially parallel to and overlies the adjacent parallel faces 11, of the upper pole tips 6a, 7a, and that it has a sliding action across said pole faces. To provide for and permit of this sliding movement, the blade portion of the armature is shown as bearing against a sheet of non-magnetic material 12 disposed in bridging relation over the pole faces. This material is preferably relatively thin, so as to bring the active portion of the armature into magnetically close relation to the pole faces. A layer of "fish paper" insulation has been found suitable for the purpose, this

being relatively stiff and exerting a frictional holding force on the armature blade sufficient to exert the desired damping tendency on the same.

To provide for the desired sliding action across the pole tips, the armature is shown as having a shaft portion 13 held in rubber bushings 14, or the like, between the lower pole tips 6b, 7b, Fig. 2, this shaft portion being threaded at the front of the unit to receive the screw 15, which secures the stylus 16 in the lower end of the reed.

In order that the various parts of the apparatus may be assembled apart from the magnet and then be applied as a unit to the magnet, the pole pieces are shown as rigidly secured together in proper spaced relation by a bridge plate 17 of non-magnetic material secured to the two pole pieces by the screws 18. This construction enables the armature and the coil to be properly assembled and the pole pieces rigidly fastened together, with the several parts in properly assembled order and these parts, then forming a single unit, to be secured as such to the magnet. The fastening of the assembled unit to the magnet is shown as accomplished by screws 19 passed freely through openings in the magnet arms into screw seats formed in the pole pieces.

When the pole pieces are attached to the magnet, the end of the armature is attracted to the side faces of the pole tips and the armature therefore becomes magnetically damped. The sliding movement of the armature across the pole faces is therefore opposed with a magnetic braking effect and by the frictional resistance interposed between the blade of the reed and the adjacent polar faces. The degree of damping may be determined by the nature and thickness of material between the pole faces and armature blade. Preferably, this material is relatively thin, so as to keep the magnetic reluctance low and hence make the device sensitive and efficient. This construction, in which the armature slides over the pole faces, across the gap, eliminates the need for any fine adjustments, such as are necessary in constructions where the armature operates within the gap and provides a simpler and more inexpensive construction.

The movement of the armature is relatively slight and the area of actual physical contact may be small, so that a proper degree of damping is obtained without impairing the efficiency of the device. While the blade of the armature is shown as substantially overlapping both polar faces at opposite sides of the gap, the degree of overlap may be less or more, as special conditions may require. The blade is usually substantially flat, so as to be parallel with the polar faces at the points or areas of contact.

By reason of the sliding action across the pole faces, the resistance to movement is substantially uniform throughout the usual range of action of the armature.

The invention also provides a particularly compact and small unit. The upper polar extensions 6a, 7a, are indicated in Figs. 1 and 2 as cut back at 20 to approximately half the normal width to concentrate the magnetic flux through the armature and to enable the location of the armature on the intermediate portion of its shaft, where it is supported by bearing portions at both sides of the same.

What is claimed is:

1. In a device of the character disclosed, the combination of pole pieces spaced to form a magnetic gap and a movable armature having a sliding engagement across the faces of said pole pieces at opposite sides of said gap.

2. In a device of the character disclosed, the combination of pole pieces spaced to form a magnetic gap, a movable armature having a sliding engagement across the faces of said pole pieces at opposite sides of said gap, there being a thin layer of non-magnetic material interposed between said armature and pole faces preventing direct physical contact between the armature and pole faces.

3. An electromagnetic unit, comprising a magnet having pole pieces separated to provide a magnetic gap and a movable armature bridging said gap and having physical engagement with the polar structure providing said gap.

4. An electromagnetic unit, comprising a magnet having pole pieces separated to provide a magnetic gap, a movable armature bridging said gap and having physical engagement with the polar structure providing said gap and a coil inductively related to said armature.

5. An electromagnetic unit, comprising a magnet having pole pieces separated to provide a magnetic gap, a movable armature bridging said gap and having physical engagement with the polar structure providing said gap and a thin layer of non-magnetic material interposed between the armature and adjacent polar faces.

6. In a device of the character disclosed, substantially C-shaped pole pieces arranged in opposition to provide two magnetic gaps,

an armature having a shaft portion mounted in one of said gaps and having a blade portion sliding across the polar faces of the other gap.

7. In a device of the character disclosed, substantially C-shaped pole pieces arranged in opposition to provide two magnetic gaps, an armature having a shaft portion mounted in one of said gaps and having a blade portion sliding across the polar faces of the other gap and a coil surrounding said armature and disposed within the hollows of the C-shaped pole pieces.

8. In an instrument of the character disclosed, magnetic pole pieces spaced to form a magnetic gap, an armature mounted for movement across said gap, non-magnetic material extending across the gap, said armature resting on said non-magnetic material, a coil inductively related to said armature and mechanical power transmission means connected with said armature.

9. An electromagnetic device, comprising a magnet having pole pieces separated to provide a magnetic gap, a thin layer of non-magnetic material bridging said gap, a vibratory armature slidably engaging said bridging layer of non-magnetic material, a winding associated with said armature and mechanical power transmission means connected with said armature.

10. An electrical instrument comprising a magnet having pole pieces separated by a magnetic gap, a sheet of insulation bridging said magnetic gap, an armature mounted for movement across said gap and bearing on said sheet of insulation and power transmission means connected with said armature.

In testimony whereof, I affix my signature.

OLIVER B. PARKER.
